UNITED STATES PATENT OFFICE.

HALBERT K. HITCHCOCK, OF TARENTUM, PENNSYLVANIA.

APPARATUS FOR APPLYING ABRASIVES TO GRINDING-MACHINES.

1,077,982.

Specification of Letters Patent. Patented Nov. 11, 1913.

Application filed May 17, 1912. Serial No. 697,868.

To all whom it may concern:

Be it known that I, HALBERT K. HITCHCOCK, a resident of Tarentum, in the county of Allegheny and State of Pennsylvania, have invented a new and useful Improvement in Apparatus for Applying Abrasives to Grinding-Machines, of which the following is a specification.

This invention relates to apparatus for grading and applying finely divided material mixed with water, and especially for grading sand or other abrading material for use with grinding machines.

In the grinding and smoothing of material requiring a fine surface, such as plate glass, marble and granite, it is desirable that after the abrasive has passed between the material to be ground, and the runners or rubbing bed, the finer particles be separated from the coarser ones and saved to be used in the finishing operation and that the coarser particles be regraded and returned to the grinding mechanism to assist in the roughing operation.

In my Patent No. 934,441, September 21, 1909, is described and claimed a process for grading fine material in suspension, and in my Patent No. 934,612, September 21, 1909, is illustrated and described certain apparatus for grading material, conducting the same to grinding apparatus and then returning it for re-use. In my application filed July 31, 1911, Serial No. 641,483, is described and claimed apparatus which is an improvement upon that illustrated and described in my Patent No. 934,612 above, which improvements include, among other features, the withdrawal of the graded material from different heights in the grading vessel or cone, such withdrawal going on simultaneously with the supply of the ungraded material to such vessel and provision for a continuous cycle of circulation of the abrasive in suspension from the grading vessel to the grinding table, and back again to and through the grading vessel.

The present application is an improvement upon the apparatus of my Patent No. 934,612 and my application Serial No. 641,483, above identified, and in its operation has a certain general resemblance and follows the broad principle of grading described in Patent No. 934,441. In the apparatus of my prior patent and application

above identified a centrifugal pump is employed for withdrawing the sand and water from the sump and forcing it up into the grading vessel through its lower end, and according to the method described an upward current of water is thus produced in the grading vessel or cone for effecting the grading operation.

The action of the sand and water is very hard on the centrifugal pump and quickly wears it out. One of the principal purposes of the present invention is to dispense with such pump so as to overcome the annoyance due to its rapid wear and to provide apparatus wherein the sand and water returned from the grinding apparatus is introduced into the grading vessel by gravity flow solely. As a consequence the upward flow in the grading vessel is not as pronounced as with the apparatus of the prior patent, but the materials are nevertheless graded.

In the accompanying drawings Figure 1 is a plan view partly broken away of apparatus embodying the present invention; Fig. 2 is in part a side elevation and in part a vertical section on the line II—II, Fig. 1; Fig. 3 is also in part an elevation and in part a vertical section on the line III—III, Fig. 1; Fig. 4 is a vertical section on the line IV—IV, Fig. 1; and Fig. 5 is a vertical elevation, Fig. 6 a similar view at right angles to Fig. 5, and Fig. 7 a top plan view of a modified arrangement of apparatus.

In the drawings 1 represents a grinding table of any suitable character, such as used for instance for grinding plate glass. Operating with the table are a pair of runners 2, as is usual with this form of apparatus.

3 is a perforated pipe or trough above the table for supplying the abrasive thereto.

4 is a gutter surrounding the table, as is usual. On one side this gutter communicates with a radial gutter 5, which has a connection through a screen or strainer 6 with a swivled bent pipe 8 for conducting the mixture of abrading material and water to the grading vessels.

9 and 10 are a pair of grading vessels mounted for vertical movement so that they can be lowered into a pit 11 to receive the sand and water coming from the grinding

table through spout 8 by gravity flow, and capable of being elevated so as to discharge to the grinding table also by gravity flow, such as through pipe or conduit 12 connected with the perforated pipe 3. In the preferred arrangement the vessels are so mounted and arranged that while one of them is down in the pit 11 to receive its charge of sand and water coming from the grinding table the other one is in elevated position to discharge to the table. The drawings show this arrangement.

The grading vessels may be elevated and lowered by any suitable mechanism. As shown in Figs. 1 to 4 the grading vessels are connected by a series of cables 14 running over guide sheaves 15 on shafts 16 mounted on the framework 17, said cables being connected to the vessels by any suitable means, such as the equalizing bars 18 and clevises 19. As a consequence, the vessels partly counterbalance each other so as to reduce the power necessary to change their relative positions. For the latter purpose each of the vessels is mounted on the upper end of a piston rod 20 of a suitable power cylinder 21, such as a hydraulic cylinder, located vertically underneath each vessel and having connected thereto a suitable pipe 22 provided with control valve 24 for admitting water or other pressure medium to the cylinder and exhausting the same therefrom. When the valves 24 are so set as to allow the pressure medium to escape from one of the cylinders 21 and to admit pressure medium to the other cylinder, the latter will be lifted, and as the vessels are connected by the cables, this allows the elevated vessel to settle and expel the pressure medium from the cylinder thereunder.

Figs. 5, 6 and 7 show a modified arrangement in which no positive power mechanism is used for changing the relative positions of the grading vessels or cones, but instead the one is elevated by the superior weight of the other one. To this end each of the vessels is provided some distance below its top with an outlet pipe 25 having a valve 26 with controlling handle 27 by means of which the level of liquid in the vessel can be lowered so as to lighten the vessel and enable the elevated one (which is full) to overbalance it so that it will pull the lighter vessel to elevated position. In this case a pair of the cables 14 which connect the two vessels are wrapped around intermediate sheaves 28 on a shaft 29 provided with a brake wheel 30 on which are a pair of reversely arranged brake bands 31 connected to arms 32 or a control lever 33. By means of this lever the friction brake can be released to permit the heavier elevated vessel to descend into the pit 11 and pull the lighter vessel to elevated position. The friction brake gives absolute control over

this movement so as to prevent a sudden drop. Said lever is locked in any position by means of the rack 34.

Many other arrangements of apparatus will readily suggest themselves for changing the relative positions of the vessels, the essential in this particular being that one vessel is in its lowermost position in the pit to receive the liquid and abradant coming from the grinding table, while the other one is in elevated position to discharge to the grinding table, thereby enabling the abradant to flow from the elevated vessel to the grinding table and from the grinding table to the lowered vessel purely by gravity flow, thereby dispensing with pumps or like means for elevating the liquid and abradant.

The spout or pipe 8 for directing the water and sand into the vessels when lowered into the pit has its end bent at right angles to its body, as clearly shown in Figs. 2 and 3, and is rotatably mounted or swiveled so that it can be swung to diametrically opposite positions to discharge into one or the other of the vessels. In Fig. 2 the full line position of pipe 8 shows the same discharging into vessel 10 which is now in the pit. When this vessel is being elevated, in its upward movement it contacts with and rotates the spout 8, turning the bent end upwardly, and as the vessel 9 descends its top flange contacts with one of the lugs 8^b on pipe 8 and turns the latter to the dotted line position, shown at 8^a, Fig. 2, so that it can then discharge into the then lowered vessel 9.

Each of the vessels is provided in its top with a transverse trough 36 sloping from the periphery to the center and communicating with opening 37 centrally of the vessel. The liquid and abradant is discharged by the spout 8 into this trough 36 and escapes through the central opening 37 into the vessel. This form of grading vessel differs from those shown in my prior patents and applications in that while provision is made for introducing a stream of liquid through the bottom of the vessel this liquid is preferably shut off while receiving the abradant. The material grades itself somewhat according to size owing to the more rapid falling of the heavier particles down through the suspending liquid. In order to understand thoroughly the action of the form of vessel shown in the drawings the principle governing the action may be briefly stated as follows: A body falling freely in vacuum has a uniformly accelerated velocity with a fixed increment of acceleration due to gravity. This acceleration is the same for all bodies. If instead of falling in a vacuum, the body falls through a liquid, its fall is resisted in proportion to its projection or area in a horizontal plane and to the extent of its wetted

surface. This resistance increases as the square of the velocity of fall. It will therefore be readily seen that as the force of gravity remains constant while the resistance of the body falling through the liquid increases as the square of the velocity, that sooner or later this resistance will equal and entirely absorb the acceleration due to gravity, after which time the body will fall 10 with a constant velocity; which may be termed its critical velocity for that liquid.

The wetted area and the projection of bodies of similar contour increases as the square of any of their similar dimensions, 15 while their weight increases as their density and the cube of their similar dimensions. It is therefore evident that this constant or critical velocity while falling in the liquid increases as the particles grow larger, so 20 that bodies having similar shapes and densities but of varying sizes falling through a vertical tank of infinite length filled with water begin to separate according to their size, the larger particles falling faster than 25 the smaller ones, and the distance separating them increasing with the time. In addition to this natural separation the heavier particles displace their own volume of water, thus creating an upward flow of water equal in 30 volume to the downward movement of the particles, the volume of this upflow increasing from the lowest particles to the highest due to the added water displaced by the particles above. This added velocity serves to 35 still further retard the downward movement of the particles higher up, so that if the quantity of solids added are sufficient and the finest particles small enough the latter will be carried up by this upward flow and 40 washed out over the top of the tank.

If the tank is of inverted cone or pyramid shape increasing in cross section upwardly, as the coarser particles fall they are crowded together by the downward converging walls 45 so that their volume forms a gradually increasing portion of the total liquid and gradually increases the upward velocity in the lower part, which magnifies the grading action. This action takes place in the grading vessels illustrated in the present application, which are of inverted cone form and in which the mixture of sand and water is introduced from the top. The larger particles falling faster than the lighter ones on 50 the principle above explained, displace the water at the bottom of the cone and cause an upward flow which is effective in separating the sand into grades according to size. As a consequence the material in the 55 vessel receiving the inflow of material at its top is undergoing a preliminary grading, and by the time the vessel is full, the material is separated into strata or zones of moderately well defined sizes, the coarser material being in the lowermost strata and the

material decreasing in size upwardly. The bulk of the very fine material and scummy matter overflows through a spout 40 discharging into a conduit 41 in the wall of the pit and leading to a sewer connection 42. 70 The finer sands are then allowed to settle somewhat and the superfluous water in the top of the vessel is drawn off through the discharge pipe 25, which discharges into a basin 43 communicating with the sewer connection. These sewer connections are made 75 on both sides of the pit so that each vessel can discharge in the same manner.

The operation just described is that which takes place when no water is admitted into the bottom of the vessel at the time it is receiving the inflow of sand and water, such as occurs in case no water supply pipe is connected to the lower end of the vessel or in case the same is closed. The preferred 80 form of apparatus, however, includes a water supply pipe 54 to the lower end of the grading vessel, as shown in the drawings, and particularly is this the case when the elevators illustrated in Figs. 1, 2, 3 and 4 are 85 employed so that this water may run continuously and thereby secure a more rapid operation and a more perfect grading in the vessel, and have the grading fully completed by the time the vessel is ready to elevate. 90 At the point where pipes 54 connect to the lower end of the vessel, are preferably placed check valves 54^a to keep the sand from backing into the pipes 54 when the water is 95 shut off.

The vessels may be of any suitable shape or size, but preferably are of inverted cone shape having sides at such an angle as to produce a considerable velocity upward from the bottom to the top where a given mixture of solids are continuously introduced at the top. It is preferred to withdraw the several grades or strata from the vessel independently or separately, so that it will not be necessary to entirely exhaust any one 100 grade before beginning to withdraw the next finer grade, as described in my application Serial No. 641,483, above identified. To this end the discharge from the cone when in its elevated position is through a series of pipes 105 45, 46 and 47 opening into the tank at different heights and all extending upwardly to 110 substantially the same level and then passing through the side wall of the cone or vessel, where they are provided with control valve mechanism indicated generally at 48, but not specifically shown or described, by 115 means of which any one of said pipes may be opened to discharge the particular grade in the strata at which the inner end of that particular pipe opens. The form of valve mechanism for controlling these pipes is not 120 125 130

specifically illustrated herein, being the same as fully illustrated, described and claimed in my application, Serial No. 641,483. All of these pipes discharge into the spout or conduit 12.

5 In order to permit of the lowering of the vessels the spout 12 is movable so that its upper end can be swung out of the position underneath the outer ends of the discharge 10 pipes of one vessel and brought into a similar position underneath the outer ends of the discharge pipes of the other vessel or cone, as indicated in dotted lines in Fig. 1. To this end the conduit 12 is swiveled at 50 and 15 its higher end is supported upon a way or guide 51 upon which it can be slid from the full line position to the dotted line position shown in Fig. 1.

20 The water connection 54 to the bottoms of the vessels not only grades the material as it flows into the vessel, but if closed when the material flows into the vessel it serves as a means of completing the grading operation after the vessel is lifted and also keeps 25 the abradant in suspension in the liquid in the vessel while being withdrawn therefrom. The pipes 54 for the two vessels are connected by flexible pipes or hose 55 to a suitable three-way cock 55^a in a supply pipe 56. 30 A two-way regulating cock 57 is provided at the lower end of the cone for connecting the cone with a discharge opening 58. The pipe 54 also extends upwardly at 59 and connects with the outer ends of the discharge 35 pipes 45, 46 and 47 for the purpose of creating an inward flow therein for removing any stoppage and cleaning them out, all as described in my application, Serial No. 641,483, above identified, and not herein specifically 40 shown or described.

The overflow from the vessels when in elevated position escapes through the overflow spouts 40 into tanks or basins 61 supported at an elevation and having pipes 62 45 connected thereto and leading to the gutter 4 and discharging thereinto at 63. Other pipes 64 also open into the tanks or basins 61 and project upwardly therein, to take the overflow from said tanks or basins, and particularly the mud and fine abradant or scum, 50 said pipes 64 having a connection at 65 to sewers 66 which also take the overflow from the cross gutter 5.

The sewers 66 and 42 are shown as extended in both directions in order to connect up a number of grinding tables and apparatus of the kind described. The fresh raw sand or other material can be supplied at any point in the system. As shown it is 55 supplied either by clam shell bucket 68 or pipes 69 emptying into hoppers 70 in position to discharge into the vessel when elevated.

60 The operation of the apparatus illustrated 65 will be readily understood from the fore-

going description. When one of the vessels is in elevated position discharging the abradant and liquid to the grinding table the other vessel is in its lowered position in the pit 11, and receives the abradant and liquid coming back from the grinding table through pipe 8. The material and water as it enters said vessel is graded according to size either partially or fully, depending upon whether water is admitted into the bottom of the vessel, into strata arranged at different heights in the vessel, the coarser particles at the bottom, and decreasing in size upwardly. The excess water, scum and other material too fine to be used escapes through the overflow spout 40 to the sewer connection 42. During the operation of supplying the abrasive and water from the elevated vessel to the table the abradant is kept in suspension in said vessel by the water supply through the pipe 54, and said pipe also supplies said vessel with water to compensate for the material withdrawn therefrom, so that said vessel remains practically constantly full. As soon as the abradant has been all or sufficiently discharged from the elevated vessel, the position of the vessels is reversed, either by means of the power cylinders shown in Figs. 1 to 4, or by partly emptying the lowermost 95 vessel to the level of the discharge spout 25, and allowing the vessels to change positions by the superior weight of the upper vessel which is full of water (and some abradant) up to the level of the upper discharge spout 100 40. Prior to changing positions, the spout 12 is moved slightly to one side and after the positions of the vessels are changed said spout is moved underneath the outer ends 105 of the discharge pipes of the fresh vessel which has just been lowered, and the operation will continue as before.

With this apparatus no pump or equivalent mechanism for handling the water and sand is required, but the flow is entirely 110 by gravity. The operation also is practically a continuous one since as soon as the abradant from one vessel is exhausted their positions can be reversed so that the freshly charged grading vessel will supply the necessary abradant. The vessels, however, will be so designed that each of them will hold sufficient water and abradant to complete the grinding of one set of glass or other material being ground, so that the reversal of 115 the vessels takes place at the time when the glass on the grinding table is being changed. This is desirable in order that the grinding operation may start with the coarsest grade in one of the vessels and be followed gradually by the higher and finer grades therein.

What I claim is:

1. Apparatus for applying abrading material to grinding and smoothing mechanism, comprising in combination, grinding 130

mechanism, a plurality of movable grading vessels, and means arranged to bring said vessels successively into position to receive the abrading material and liquid coming from the grinding mechanism and to bring said vessels successively into position to discharge to the grinding mechanism.

2. Apparatus for applying abrading material to grinding and smoothing mechanism, comprising in combination, grinding mechanism, a pair of grading vessels, and means arranged to bring said vessels successively into position to receive the abrading material and liquid from the grinding mechanism and to discharge to the grinding mechanism, said means being so arranged that when one of said vessels is in position to discharge to the grinding mechanism the other vessel is in position to receive the abrading material and liquid coming from the grinding mechanism.

3. Apparatus for applying abrading material to grinding and smoothing mechanism, comprising in combination, grinding mechanism, a grading vessel, and mechanism for lowering said vessel to receive the abrading material and liquid coming from the grinding mechanism by gravity flow thereto and for then elevating said grading vessel to discharge to the grinding mechanism by gravity flow.

4. Apparatus for applying abrading material to grinding and smoothing mechanism, comprising in combination grinding mechanism, a pair of grading vessels mounted for vertical movement and connected so that when one is elevated the other is lowered, and mechanism for alternately reversing the positions of said grading vessels, the one in position to receive the abrading mixture coming from the grinding mechanism and the other to discharge to the grinding mechanism.

5. Apparatus for applying abrading material to grinding and smoothing mechanism, comprising in combination, grinding mechanism, a pair of grading vessels mounted for up and down movement, a conduit for conducting the abrading mixture from the grinding mechanism, an elevated conduit for conducting the abrading mixture to the grinding mechanism, and mechanism arranged to alternately raise and lower said grading vessels in succession to bring the lowermost one into position to receive the abrading mixture from the first named conduit and the elevated one of said vessels into position to discharge to the elevated conduit.

6. Apparatus for applying abrading material to grinding and smoothing mechanism, comprising in combination, grinding mechanism, a pair of grading vessels mounted for up and down movement, a spout in position to receive the abrading mixture from the grinding mechanism and movable

to discharge into either of said grading vessels when in lowermost position, and an elevated spout for conducting the abrading mixture to the grinding mechanism and movable to receive said mixture from either of said grading vessels when in elevated position.

7. Apparatus for applying abrading material to grinding and smoothing mechanism, comprising in combination, grinding mechanism, a plurality of movable grading vessels, means arranged to bring said vessels successively into position to receive the abrading mixture coming from the grinding mechanism and into position to discharge to the grinding mechanism, and conduits arranged to catch the overflow from said vessels when in both positions.

8. Apparatus for applying abrading material to grinding and smoothing mechanism, comprising in combination, grinding mechanism, a pair of grading vessels arranged for up and down movement and connected together so that when one rises the other drops, and conduits arranged to conduct the abrading mixture from the grinding mechanism to the vessel in lowermost position and from the vessel in elevated position to the grinding mechanism, and a water supply to the bottoms of both vessels.

9. Apparatus for applying abrading material to grinding and smoothing mechanism, comprising in combination, grinding mechanism, a pair of grading vessels arranged for up and down movement and connected together so that when one rises the other drops, conduits arranged to conduct the abrading mixture from the grinding mechanism to the vessel in lowermost position and from the vessel in elevated position to the grinding mechanism, a water supply to the bottoms of said vessels, and conduits arranged to receive the overflow from said vessels in both elevated and lowered position.

10. Apparatus for applying abrading material to grinding and smoothing mechanism, comprising in combination, grinding mechanism, a pair of grading vessels mounted for up and down movement, connections between said vessels so arranged that when one of said vessels is elevated the other drops, conduits arranged to conduct the abrading mixture from the grinding mechanism to the vessel in lowermost position and from the vessel in elevated position to the grinding mechanism, and a valved outlet from each of said vessels below its upper end, whereby the vessel in lowermost position can be partly emptied to be counterbalanced by the vessel in uppermost position.

11. Apparatus for applying abrading material to grinding and smoothing mechanism, comprising in combination, grinding

mechanism, a pair of grading vessels mounted for up and down movement, connections between said vessels so arranged that when one of said vessels is lifted the other drops, 5 conduits arranged to conduct the abrading mixture from the grinding mechanism to the vessel in lowermost position and from the vessel in elevated position to the grinding mechanism, a valved outlet from each of 10 said vessels below its upper end, whereby the vessel in lowermost position can be partly emptied to be counterbalanced by the vessel in uppermost position, and water supply connections to the bottoms of both of 15 said vessels.

12. Apparatus for applying abrading material to grinding and smoothing mechanism, comprising in combination, grinding mechanism, a pair of grading vessels, means 20 for maintaining the abrading material in suspension in liquid in both of said vessels, and means for conducting the material while in suspension in said liquid alternately from said vessels to said grinding mechanism.

13. Apparatus for applying abrading material to grinding and smoothing mechanism, comprising in combination, grinding mechanism, a pair of grading vessels, means for maintaining the abrading material in 30 suspension in liquid in both of said vessels, means for conducting the material while in suspension in said liquid alternately from said vessels to said grinding mechanism, and a conduit for receiving the abrading 35 material from the grinding mechanism and conducting the same alternately to said vessels.

14. Apparatus for applying abrading material to grinding and smoothing mechanism, comprising in combination, grinding mechanism, a pair of grading vessels, means 40 for introducing liquid into both of said vessels to maintain the abrading material in suspension therein, and means for conducting 45 the abrading material while in suspension in said liquid alternately from said vessels to the grinding mechanism.

15. Apparatus for applying abrading material to grinding and smoothing mechanism, comprising in combination, grinding mechanism, a pair of grading vessels, means 50 for introducing liquid into both of said vessels to maintain the abrading material in suspension therein, means for conducting 55 the abrading material while in suspension in said liquid alternately from said vessels to the grinding mechanism, and a conduit for receiving the abrading material from

the grinding mechanism and conducting the same alternately to said vessels. 60

16. Apparatus for applying abrading material to grinding and smoothing mechanism, comprising in combination, grinding mechanism, a pair of grading vessels arranged to alternately receive the abrading 65 material from the grinding mechanism, means for producing in both of said grading vessels a downward flow or travel of the material relative to the liquid, and conduits for withdrawing material and liquid 70 alternately from said vessels and conducting the same to the grinding mechanism.

17. Apparatus for applying abrading material to grinding and smoothing mechanism, comprising in combination, grinding 75 mechanism, a pair of grading vessels arranged to alternately receive abrading material from the grinding mechanism, means for producing in both of said grading vessels a downward flow or travel of the material relative to the liquid, and means arranged to withdraw the material and liquid 80 from different strata in both of said vessels and conduct the same alternately from said vessels to the grinding mechanism. 85

18. Apparatus for applying abrading material to grinding and smoothing mechanism, comprising in combination, grinding mechanism, a pair of grading vessels arranged to alternately receive abrading 90 material from the grinding mechanism, means for producing in both of said vessels an upward flow of liquid, and conduits for withdrawing the material and liquid alternately from said vessels and conducting the same 95 to the grinding mechanism.

19. Apparatus for applying abrading material to grinding and smoothing mechanism, comprising in combination, grinding mechanism, a pair of grading vessels arranged to alternately receive abrading material from the grinding mechanism, means for producing in both of said grading vessels an upward flow of liquid, means arranged to withdraw the material and liquid 100 from different strata in said grading vessels, and a conduit for conducting the material and liquid alternately from said vessels to said grinding mechanism. 105

In testimony whereof, I have hereunto set my hand.

HALBERT K. HITCHCOCK.
